DESIGN FOR A STORE FRONT

Kenneth E. Bemis, Oakland, Calif.

Application July 5, 1940, Serial No. 93,451

Term of patent 14 years

To all whom it may concern:

Be it known that I, Kenneth E. Bemis, a citizen of the United States, residing at Oakland, in the county of Alameda and State of California, have invented a new, original, and ornamental Design for Store Front, of which the following is a specification, reference being had to the accompanying drawing, forming part thereof.

Fig. 1 is a front elevational view of a store front showing my new design;

Fig. 2 is a top plan view thereof, the left wing of which is of the same appearance as the wing shown in Fig. 1.

I claim:

The ornamental design for a store front, as shown and described.

KENNETH E. BEMIS.
